CARTON

Phillip R. Smythe, Akron, Iowa

Application October 29, 1934, Serial No. 750,427

1 Claim. (Cl. 229—15)

My invention relates to a carton of the type having a hinged flap and refers particularly to a carton of heavy paper.

An object of my invention is to provide a carton which is readily folded for packing purposes and which is of strong and durable construction.

A further object of my invention is to provide means for retaining the carton in closed position, maintaining a rigid structure.

10 A further object of my invention is to provide means for opening or closing the carton quickly and conveniently.

15 A further object of my invention is to provide a carton of this type which can be handled roughly without injury to the same.

A further object of my invention is to simplify the construction of this invention as much as possible to make the same reasonable in the cost of manufacture.

20 With these and other objects in view, my invention consists in the construction, arrangement and combination of the various parts of my device, whereby the objects contemplated are attained, as hereinafter more fully set forth, pointed out in my claim, and illustrated in the accompanying drawing, in which:

Figure 1 is a plan view of the carton in its open position.

Figure 2 is a sectional view of Figure 1 taken 30 along the lines 2—2,

Figure 3 is a plan view of the carton in its closed position.

Figure 4 is an enlarged detail view taken along the lines 4—4 of Figure 1, and

35 Figure 5 is a plan view showing the collapsing feature of the carton.

In its preferred form, the carton is made of heavy cardboard or paper, although it will be understood that it can be made of other materials as 40 well.

I have used the character 10 to represent the end walls of the carton, and 11, the side walls thereof. Affixed between the walls 11 is the member 12 which includes the flanges 13 bent 45 positively as shown and attached to the walls 11 with the staples 14.

The upper and lower ends of the partition 12 are looped at 15 along the length thereof and attached with staples at 16. The loop 15 receives 50 the wire form 17 which is a continuous piece of wire bent into the loops 18 of which, in this construction, there are four. These loops extend through the openings 19 which are cut out from the paper or cardboard loop 15.

55 It will now be seen that these loops 18 project

slightly above the upper and lower edges of the carton as shown.

The carton also includes the side flaps 20 and the end flaps 21. The side flaps 20 include circular openings 22, and the end flaps include the openings 23. The end flaps 21 are adapted to overlap the central partition 12, but the side flaps 20 fall to the position as indicated by the dotted lines at 24 when closed and do not overlap. The flaps 20 are indented at 25 to insure a neat closure. The 10 end flaps 21 can be attached to the carton as shown in Figure 2 where they include the U shaped extremities 26 which receive the integral U shaped extensions 27 of the end walls 10. These members are attached by means of the staples 28. 15

The openings 22 and 23 are so positioned on the flaps that when they are closed, they will all overlap the loops 18 and receive the same.

For instance, in closing the carton, the side flaps 20 are first folded inwardly so that the openings 22 receive the respective loops, then the end flaps 21 are folded inwardly, first one flap with its corresponding openings receiving the loops, and then the other. This feature is illustrated more clearly in Figures 2 and 4. After this operation, the wire bolt 29 is passed through the upper end of the loop 18, thereby closing the carton effectively. 20 25

The bolt 29 includes the handle portion 30 to facilitate removal and insertion thereof. After 30 the bolt 29 is once inserted, the natural tendency of the flat members is to exert resilient force against the bolt so that it will be maintained tightly and in firm engagement so that the carton can be handled quite roughly without slipping or opening of the flaps. 35

It will be understood that the section taken on the lines 4—4 is taken with the flaps in the closed position.

It will be understood that this construction 40 can be followed using this particular flap arrangement on the top only instead of on both bottom and top as shown in the drawing, in case it is desired to use a stiff carton.

It will be noted from Figure 5 that this type of 45 carton can be readily collapsed when the flaps are open to permit flattening of the entire carton for shipping purposes. This figure shows the beginning of the collapsing operation, and it will be noted that the hinging effects of the partition 12 50 and the end walls 10 permit of this feature.

It will be noted that when in closed position, the incorporation of the openings together with the received loops and the locking bolt provides a positive rigid structure which absorbs all strains 55

in a highly efficient manner, and, yet, which can be opened by one simple operation. Also the overlapping relation of the flaps provides a comparatively tight closure.

- 5 It will be also noted that although the carton is collapsible, the feature of the partition, etc., provides strength to the structure as well as the other features mentioned.

It will now be seen that I have provided a carton which is strong and durable and of very inexpensive construction, and it will also be seen that this carton can be folded when not in use, and which can be readily opened or locked.

It will be seen further that I have provided such a carton which can be handled roughly without injury to the carton or its contents, and which can be quickly opened or locked.

Some changes may be made in the construc-

tion and arrangement of the parts of my invention without departing from the real spirit and purpose of my invention, and it is my intention to cover by my claim any modified forms of structure or use of mechanical equivalents, which may be reasonably included within their scope. 5

I claim as my invention:

A carton comprising parallel side walls and end walls, a partition parallel to the end walls and hinged to the side walls including bent over 10 edges, an integral wire form including a plurality of loops received within the bent over edges with said loops projecting above the partition, end and side flaps hinged to end and side walls having openings adapted to receive said loops when the 15 carton is closed, and a locking bolt receivable through said loops and above said flaps.

PHILLIP R. SMYTHE.
